ATTORNEY

UNITED STATES PATENT OFFICE.

FRANK RHIND, OF BRIDGEPORT, CONNECTICUT, ASSIGNOR OF ONE-HALF
TO THE BRIDGEPORT BRASS COMPANY, OF SAME PLACE.

DESIGN FOR A LANTERN-REFLECTOR.

SPECIFICATION forming part of Design No. 31,588, dated October 3, 1899.

Application filed September 5, 1899. Serial No. 729,563. Term of patent 14 years.

To all whom it may concern:

Be it known that I, FRANK RHIND, a citizen of the United States, residing at Bridgeport, Connecticut, have invented and produced a new and original Design for a Lantern-Reflector, of which the following is a specification.

In the accompanying drawings, Figure I is a side elevation of a lantern-reflector, showing my design. Fig. II is a front elevation of the same.

1 designates a cup-shaped nearly hemispherical body portion provided at its smaller

end with a cylindric portion 2 and at its larger open end with a bead 3.

The leading feature of my design is the cup-shaped portion formed with a cylindric portion of reduced diameter at its smaller end.

What I claim is—

The design for a lantern-reflector herein described and shown.

FRANK RHIND.
